UNITED STATES PATENT OFFICE.

PHILIP H. YAWMAN, OF ROCHESTER, NEW YORK, ASSIGNOR TO THE OFFICE
SPECIALTY MANUFACTURING COMPANY, OF NEW YORK.

PUNCH.

SPECIFICATION forming part of Letters Patent No. 444,891, dated January 20, 1891.

Application filed May 20, 1890. Serial No. 362,609. (No model.)

To all whom it may concern:

Be it known that I, PHILIP H. YAWMAN, of Rochester, in the county of Monroe and State of New York, have invented certain Improvements in Paper-Punches, of which the following is a specification.

This invention relates more particularly to a punch designed to produce two or more holes or perforations simultaneously in a sheet or 10 a series of sheets and in definite relation to the edge of the sheet. It is intended more particularly for punching letter-sheets and other papers intended for application to the well-known Shannon letter-files and similar 15 files in which there are two filing arches or wires to receive the sheets.

The special aims of the present improvement are to simplify the construction, reduce the cost of manufacture, and adapt the device 20 for punching through a large number of sheets at one time.

In the accompanying drawings, Figure 1 is a perspective view of the improved punch. Fig. 2 is a front elevation of the same, one 25 side being shown in vertical section. Fig. 3 is a vertical cross-section on the line $\alpha\alpha$ of Fig. 2.

Referring to the drawings, A represents a flat rectangular base cast complete in one piece, 30 with two standards a' on its top, and with a cavity or chamber a^3 in its underside. This bottom chamber, designed to receive and retain the punchings, is closed by a removable bottom plate a^3 , arranged to slide edgewise 35 between the undercut shoulders or lips a^4 , so that although held firmly in place it may be readily withdrawn to discharge the contents of the chamber. Each of the standards a' is arranged to overhang the base-plate at the 40 forward end, so that the edges of the sheet to be punched may be introduced beneath them, and in each of these overhanging ends is mounted a vertically-sliding solid punch B, the lower end of which is arranged to descend 45 through a hole b in the base-plate.

C represents a flat steel plate secured to the upper face of the bed-plate by a screw c or equivalent fastening, and provided with holes or dies c' , registering with the holes b 50 and adapted to co-operate with the punches in producing the required perforations in the

sheets. The plate C is projected at one end beyond the base and turned upward, as shown at c^2 , to serve as a gage or stop against which to rest the edge of the paper in order 55 to insure the formation of the holes at the exact point required in the sheet.

Each of the punches is connected at its upper end by a horizontal pin d to the lower end of a yoke D, which partly encircles a 60 horizontal bar or shaft E, provided with an operating-handle e , and sustained at its two ends by eccentrically-located screws e' , passing through the standards a' , so that by turning the shaft to and fro it causes the 65 yokes to raise or lower the two punches simultaneously. The shaft E, which is in effect an eccentric, is commonly made of a bar of round steel, its ends being grooved circumferentially to receive the yokes D. The yokes are 70 punched from sheet metal with a slot or opening in one side to admit of their being slipped over the shaft. After being thus applied they are slightly closed or compressed to prevent their escape. 75

In place of the plate C, any other suitable gage may be employed to determine the position of the sheet. The details may be otherwise modified, as the skill or taste of the mechanic may suggest, provided no material 80 departure is made from the construction and mode of operation herein described.

While I have illustrated and in most cases propose to use the two punches, it is manifest that where it is required to produce a 85 single hole one of the punches and its guide may be omitted without in any manner affecting the construction or operation of the remaining parts. My invention therefore contemplates single as well as double punches 90 guided and actuated by the devices shown.

Having thus described my invention, what I claim is—

1. The duplex paper-punch consisting of the base-plate, its standards, the sliding 95 punches in said standards, the eccentric-shaft sustained by the standards, and the yokes or links connecting the two punches with the shaft.

2. In a paper-punch, the combination of a 100 base-plate and a rigid standard overhanging the same and integral therewith, a punch

sliding vertically within the standard, an eccentric connected to the standard, and a yoke or link pivotally connected at one end to the punch and at the opposite end embracing the eccentric.

3. In a paper-punch, the combination of a standard, a sliding punch guided therein, a circumferentially grooved eccentric, and a yoke or link jointed to the punch, provided with a side opening to receive the eccentric and contracted upon the latter to prevent its escape.

4. A duplex punch consisting of the base-plate having the standards and the bottom

chamber, the eccentric-shaft, the links connected thereto, the punch connected to the links and guided in the standards, and the gage-plate fixed to the bed-plate and provided with openings through which the punches act to deliver the punchings into the base-chamber.

In testimony whereof I hereunto set my hand this 2d day of May, 1890, in the presence of two attesting witnesses.

PHILIP H. YAWMAN.
